UNITED STATES PATENT OFFICE.

CHARLES HARLEY, OF LUDINGTON, MICHIGAN, ASSIGNOR TO LOUIS G. MERRITT, OF LOCKPORT, NEW YORK.

DRYING-KILN.

1,194,734.

Specification of Letters Patent. Patented Aug. 15, 1916.

Application filed August 28, 1915. Serial No. 47,736.

To all whom it may concern:

Be it known that I, CHARLES HARLEY, a citizen of the United States, residing at Ludington, in the county of Mason and 5 State of Michigan, have invented certain new and useful Improvements in Drying-Kilns, of which the following is a full, clear, and exact description, such as will enable others skilled in the art to which it 10 appertains to make and use the same.

The present invention relates to improvements in drying kilns of a type especially adapted and designed for the purpose of drying veneer.

15 The object of the invention is to simplify the construction and operation of apparatus now in use for this purpose by compactly combining and arranging the component parts of the apparatus in such a manner as 20 to produce a durable structure which may be easily and efficiently operated and, in which the heating devices are of a form particularly designed to exert a uniform pressing and drying effect upon each sheet of 25 veneer.

Other objects will be in part obvious and in part pointed out hereinafter.

The invention accordingly consists in the 30 features of construction, combinations of elements and arrangement of parts which will be exemplified in the construction hereinafter set forth, and the scope of the application of which will be indicated in the following claims.

35 In the accompanying drawings, wherein is illustrated one of the various possible embodiments of this invention, Figure 1 is a front elevation thereof; Fig. 2 is a plan view thereof; and Fig. 3 is a portion of a 40 side elevation thereof.

Similar reference characters refer to similar parts throughout the several views of the drawing.

45 Before proceeding to a description of the construction of an apparatus embodying the invention, it may be stated briefly that it embraces a series of fixed drying platens, each composed of coils of pipe placed one above the other at suitable distances apart, and adapted to be properly heated. Co- 50 operating with the fixed platens is a series of movable platens equal in number and similarly constructed. Suitable mechanism is provided whereby the movable platens 55 may be lowered to rest upon veneer placed

upon the upper surfaces of the fixed platens, in which position of the apparatus there will be a series of spaces between the upper surfaces of the movable platens and the lower surfaces of the fixed platens, which spaces may be filled with layers of veneer to be subsequently pressed and dried by raising the movable platens so that they shall make contact with the lower surfaces of the fixed platens. 60

Referring now to the drawings, reference numeral 1 indicates a rectangular base of the machine, which may be of any desired construction. At the corners of the base are placed vertical columns 2 which are connected at their upper ends by braces 3. These columns are adapted to support the fixed drying platens 4, each of which is composed of a plurality of pipes, as will be subsequently described. The means for supporting these platens comprises a plurality of substantially horizontal "headers" or supporting bars 5, having at each end a pair of perforated flanges 6 through which attaching bolts 7 are passed and secured to the upright columns by nuts 8. The headers are perforated at regular intervals (as at 9,) to receive the pipes composing the fixed platens, and the upper and lower edges of the headers are corrugated for coöperation 75 with the pipes of the movable platens, as will presently appear. 80

In order that a heating medium may be conducted through the platens, each one of them is formed as a continuous coil by connecting the pipes thereof together by means of return bends 10 which are alternately disposed on opposite sides of the platen, as shown most clearly in the plan view, Fig. 2. At the ends of the coil composing each 90 platen are placed elbows 11. One elbow of the upper platen is connected to a steam supply system through a pipe 12, while the other end of the same platen is connected by pipe 13 to one end of the coil, composing 100 the adjacent fixed platen 4. The opposite end of the last-named platen is similarly connected by means of a pipe 13 to an end of the fixed platen next below, and this system of connection is carried throughout the 105 entire series of fixed platens until the end of the lowermost one is reached, at which point there is a connection 14 passing to the steam supply system. It will thus be seen that there is a continuous passage for steam 110

throughout all of the pipes composing the series of fixed platens. Suitable steam traps and drip cocks to drain off the water of condensation may be provided, but are not illustrated, as they are well known.

To prevent the pipes of the platens from coming directly in contact with veneer with the danger of too rapid drying and perhaps discoloration at the points of contact, the 10 pipes are covered with material having openings to permit passage of currents of heated and moisture-laden air through the platen. It has been found that wire mesh, as shown at 15, serves this purpose satisfactorily, and it may be easily attached by simply drawing it around the row of pipes composing the platen and attaching the edges together, as at 16, where the fastening will not come in contact with the veneer. 15

20 It will be understood, however, that the invention is not limited to the above mode of attachment, since any other suitable mode could be used without departing from the scope of the invention.

25 Passing now to a consideration of the movable platens, which are indicated by reference numeral 17, it will be seen that they are equal in number to the fixed platens, and while five of each are shown, it will be 30 understood that the number may be increased or decreased as may be necessary or desirable. The movable platens are composed of a plurality of pipes connected at their ends by return bends 10' disposed on 35 opposite sides of the machine so as to form a continuous coil precisely as in the case of the fixed platens, and steam can be passed through the movable platens by means of the connections 18 at the top and 19 at the 40 bottom. The intermediate platens are connected by pipes 20 in a manner analogous to that used with the fixed platens. It will be noted, however, that the top connection 18 comprises three elbows and a considerable length of pipe. The purpose of this is 45 to permit a certain amount of flexibility to the connection when the movable platens are raised or lowered, and a similar expedient may be adopted in regard to the other connecting pipe 19, although it has not been 50 illustrated.

The movable platens 17 are supported upon a suspended framework composed of four vertical members 21, to which, on opposite sides of the machine, a series of substantially horizontal angle bars 22 are attached. The return bends 10' of the movable platens rest directly upon these angle bars, as shown most clearly in Figs. 1 and 2.

60 For raising and lowering the movable platens there is provided on each side of the machine a shaft 23 mounted in brackets 24 attached to the upper ends of the columns 2. Fixed to the shafts 23 and in line with the 65 vertical members 21 of the movable frame

are winding drums 25 from each of which chains 26 pass to the ends of the said vertical members. Also attached to the shafts 23 are arms 27, from the outer ends of which weights 28 are suspended by chains 70 or ropes 29, the purpose of these weights being to counterbalance to any desired degree the weight of the movable platens and the frame supporting the same. At the base of the machine and extending at right angles to the shafts 23 is a shaft 30 fixed in bearings 31 on two of the upright columns 2. At each end of the shaft 30 is a winding drum 32 from which a chain 33 passes over a companion drum 34 on the end of the corresponding shaft 23. Attached at one end of the shaft 30 is a lever 35 for rotating the same. This lever may be provided with any well known latching device 36 by which it may be locked in any position.

75 The pipes composing the series of movable platens 17 are covered with wire mesh or other suitable material in a manner similar to that described for the fixed platens. It will also be seen, especially from Fig. 2, 90 that the pipes of the movable platens are somewhat longer than those of the fixed platens, and from Fig. 3 it will be seen that the depressions in the horizontal supporting bars 5 permit the pipes of the movable 95 platens to approach closely the pipes of the fixed platens, while the lengthened pipes of the former also prevent any interference between the return bends thereof and the return bends of the fixed platens.

100 It will also be seen from the construction shown that the movable platens 17 are simply resting upon the angle bars 22, and that when they are lowered upon the fixed platens 4 by a proper motion of the operating lever 105 35 and the resultant unwinding of the chains 26 upon the drums 25 of the shafts 23 that the supporting frame of the movable platens may be lowered away from the same so that these platens rest entirely upon the fixed 110 platens. On account of the construction of the movable platens with the return bends at the ends they will possess sufficient flexibility so that, in the position just described, 115 they will adapt themselves to any variations in the thickness of the sheets of veneer held between them and the fixed platens. When, however, the movable platens are moved in a reverse direction; that is, so that their opposite surfaces come in contact with the 120 lower surfaces of the fixed platens, no such adjustment is possible. Therefore, if the veneer to be dried possesses considerable irregularities in thickness, it may be advisable to operate the machine only by lowering the movable platens upon the fixed platens instead of attempting to use the other possible operation of raising the movable platens against the lower surfaces of the fixed platens. This, of course, does not 125 130

5 permit fresh layers of veneer to be inserted while others are drying, but this disadvantage may be compensated for by the uniform pressing effect obtained upon layers of veneer exhibiting irregularities in thickness.

10 While the machine may be operated in the manner just described, the usual operation thereof will make use of both upper and lower surfaces of both the fixed and movable platens in the manner already indicated but which may be reviewed in conclusion.

15 The counter-balancing weights 28 are preferably made sufficiently heavy to more than make up for the weight of the movable platens 17 and the frame upon which they are mounted. Thus, the effect of the counter-balancing weights is to tend to raise the movable platens so that their upper surfaces come in proximity to the adjacent under surfaces of the fixed platens and any veneer that has been placed upon the former is firmly held and dried. The pressing effect will, of course, depend upon the excess 25 weight of the counter-balances over the weight of the movable platens and frame.

20 While the above-described drying operation is taking place fresh layers of veneer may be placed in position upon the upper wire mesh surfaces of the fixed platens. By subsequently rotating the shaft 30 by the lever 35 the counter-balancing weights may be raised sufficiently to permit the movable platens to move downwardly until they rest 25 upon the layers of veneer which have just been placed upon the upper surfaces of the fixed platens. While fresh layers of veneer are thus being dried, those previously dried may be removed and new layers put in place 40 for subsequent drying upon the next operation of the machine.

45 It may be found in practice that as the veneer shrinks while drying the pressure upon it should be intermittently relieved. This may be done when desired by a slight rotation of the shaft 30 in the proper direction by the lever 35.

50 In order to retain as much heat as possible within the apparatus it will be understood that a shed or other inclosure of any desired construction may be provided.

55 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

60 It is also to be understood that the language used in the following claims is intended to cover all of the generic and specific features of the invention herein described and all statements of the scope of

the invention, which, as a matter of language, might be said to fall therebetween.

Having described my invention, what I claim as new and desire to secure by Letters Patent is:

1. A drying-kiln having, in combination, a plurality of fixed platens and a plurality of movable platens arranged one above the other and each comprising a continuous coil, means for raising and lowering said movable platens, and means permitting the passage of a heating medium through each of said platens. 70

2. A drying-kiln having, in combination, alternately arranged fixed and movable platens, each comprising a continuous coil, means for suspending the movable platens as a unit, means for moving the movable platens in juxtaposition to the fixed platens, and means permitting the passage of a heating medium through each of said platens. 80

3. A drying-kiln having, in combination, alternately arranged fixed and movable platens, each comprising a continuous coil, means for suspending the movable platens as a unit, means for counter-balancing the weight of said movable platens, means for moving the movable platens in juxtaposition to the fixed platens, and means permitting the passage of a heating medium through each of said platens. 90

4. A drying-kiln having, in combination, alternately arranged rows of fixed and movable pipes, the pipes of each row being connected together to form a continuous coil, means permitting the passage of a heating medium through each coil, counter-balanced means for supporting the rows of movable pipes as a unit, and means for moving said last-named rows into contact with the rows of fixed pipes. 100

5. A drying-kiln having, in combination, horizontally arranged platens each composed of parallel pipes, the ends of adjacent pipes of each platen being coupled together to form a continuous coil, fixed and movable frames to which said platens are alternately connected, counter-balanced means for supporting said movable frame, and means for raising and lowering said movable frame in order that the platens connected thereto may be placed in contact alternately with the upper and lower surfaces of the fixed platens. 115

6. A drying-kiln having, in combination, horizontally arranged platens each composed of parallel pipes, the ends of adjacent pipes of each platen being coupled together to form a continuous coil, and the pipes of each platen being arranged in staggered relation to those of adjacent platens, a movable frame comprising substantially horizontal bars upon which alternate platens are supported, means for raising and lowering said frame, and a fixed frame comprising 125 130

substantially horizontal bars to which the remaining platens are connected, the upper and lower surfaces of said last-named bars being corrugated to permit the movable platens to be brought closely in proximity to the fixed platens when said movable frame is raised and lowered.

7. A drying-kiln having, in combination, a fixed platen and a movable platen arranged one above the other, means for heating each of said platens, means for raising and lowering the movable platen, and a reticulated metal covering for each platen forming a substantially plane drying and pressing surface.

8. A veneer drying-kiln having, in combination, a fixed platen and a movable platen arranged one above the other, means for heating each platen, means for raising and lowering the movable platen, and a wire mesh covering attached to each platen for supporting veneer and allowing currents of heated air to pass through said platen.

9. In apparatus for drying veneer, in combination, a fixed frame and a movable frame, each of said frames comprising upright columns and substantially horizontal supporting bars attached thereto, a plurality of fixed bearings, shafts mounted in said bearings, means attached to said shafts and to the upright columns of said movable frame, means for rotating said shafts whereby said movable frame is moved relatively to said fixed frame, and drying platens supported by said horizontal bars, said platens being so formed and mounted that they may adapt themselves to variations in the thickness of sheets of veneer held between them.

10. A drying-kiln having, in combination, a series of supporting bars, drying coils, each comprising a plurality of tubes, a plurality of return bends adapted to rest upon said supporting bars and to which said tubes are connected, and means attached to said tubes forming a substantially plane drying and pressing surface.

11. A drying-kiln having, in combination, a series of supporting bars, drying coils, each comprising a plurality of tubes, a plurality of return bends adapted to rest upon said supporting bars and to which said tubes are connected, and wire mesh attached to said tubes forming a substantially plane drying and pressing surface.

12. A drying-kiln having, in combination, supporting bars, a plurality of hollow members engaging said supporting bars, a plurality of pipes connected to said hollow members in such a manner as to form a continuous coil, and a covering extending over the upper and lower surfaces of said coil.

13. A drying-kiln having, in combination, supporting bars, a plurality of hollow members engaging said supporting bars, a plurality of pipes connected to said hollow

members in such a manner as to form a continuous coil, and a covering composed of reticulated metal extending over the upper and lower surfaces of said coil.

14. A drying-kiln having, in combination, a series of substantially horizontal supporting bars on opposite sides thereof, a plurality of return bends supported upon said bars, a plurality of pipes connecting said return bends on opposite sides of the machine, said return bends on one side of the machine being disposed with relation to corresponding bends on the other side of the machine in such a manner that the pipes connecting them form a continuous coil, and a reticulated metal covering attached to said pipes.

15. A drying-kiln having, in combination, a pair of supporting frames, platens carried by each of said frames, means for moving one of said frames relatively to the other so that a portion of the platens may rest upon the remainder of the platens, and means whereby said platens automatically adjust themselves to any variations of the surface upon which they rest.

16. A drying-kiln having, in combination, a fixed frame, a movable frame, each of said frames comprising upright columns and substantially horizontal bars, a power shaft mounted upon said fixed frame, a plurality of shafts mounted at the top of said fixed frame, counterweights attached to said top shafts, means for rotating said power shaft, operative connections between said power shaft and said plurality of shafts, means connecting said movable frame to said plurality of shafts, and drying platens supported upon said horizontal bars, the platens carried by said movable frame being so constructed and mounted that they may adapt themselves to variations in the thickness of material held between them and the platens of said fixed frame.

17. A drying-kiln having, in combination, a plurality of frames, each comprising upright columns and substantially horizontal supporting bars attached thereto, drying platens carried upon said supporting bars, each of said platens comprising a plurality of pipes, a reticulated metal covering attached to said pipes, and return bends to which said pipes are connected, said return bends being formed and those of one platen being so disposed with relation to those of an adjacent platen that the coverings of said platens may come into contact without contact between the return bends of said adjacent platens.

18. A drying-kiln having, in combination, a plurality of frames, each comprising upright columns and substantially horizontal supporting bars attached thereto, drying platens carried upon said supporting bars, each of said platens comprising a plurality

- of pipes, a wire mesh covering attached to said pipes, and return bends to which said pipes are connected, said return bends being formed and those of one platen being so disposed with relation to those of an adjacent platen that the coverings of said platens may come into contact without contact between the return bends of said adjacent platens.
19. A drying-kiln having, in combination, a plurality of frames, a plurality of drying platens carried by each frame, each platen comprising a plurality of pipes arranged adjacent to one another in a substantially horizontal plane, a covering attached to said pipes forming a substantially plane drying and pressing surface, and means connecting the adjacent ends of said pipes, the connecting means of each platen being offset with respect to the connecting means of adjacent platens so that the surfaces of said platens may be brought into contact.
20. In apparatus for drying veneer, in combination, a plurality of drying coils, each of said coils comprising a plurality of tubes, a plurality of return bends to which said tubes are connected, supporting bars upon which said return bends are adapted to rest, and means attached to said tubes to prevent them from coming in contact with veneer.
21. In apparatus for drying veneer, in combination, a plurality of drying coils, each of said coils comprising a plurality of tubes, a plurality of return bends to which said tubes are connected, supporting bars upon which said return bends are adapted to rest, and wire mesh attached to said tubes to prevent them from coming in contact with veneer.
22. In apparatus for drying veneer, in combination, a series of supporting bars, drying platens adapted to rest upon said bars, each of said platens comprising a plurality of tubes, a plurality of return bends connecting the ends of said tubes and adapted to engage said bars, and wire mesh attached to said tubes.
23. In apparatus for drying veneer, in combination, a series of supporting bars, drying platens adapted to rest on said bars, each of said platens comprising a plurality of tubes, a plurality of return bends connecting the ends of said tubes and adapted to engage said bars, and means fastened to said tubes forming a substantially plane drying and pressing surface of said platen.
24. In apparatus for drying veneer, in combination, a series of supporting bars, a plurality of hollow members adapted to engage said supporting bars, a plurality of pipes connected to said hollow members, and means fastened to said pipes forming a substantially plane drying and pressing surface.
25. In apparatus for drying veneer, in combination, a series of supporting bars, a plurality of hollow members adapted to engage said supporting bars, a plurality of pipes connected to said hollow members, and wire mesh fastened to said pipes forming a substantially plane drying and pressing surface.
26. In apparatus for drying veneer, in combination, a series of substantially horizontal supporting bars on opposite sides of the machine, a plurality of return bends adapted to be supported upon said bars, a plurality of pipes connecting said return bends on opposite sides of the machine, said return bends at one side of the machine being disposed with relation to corresponding bends on the other side of the machine in such a manner that the pipes connecting them form a continuous coil, and means fastened to said pipes forming a substantially plane drying and pressing surface.
27. In apparatus for drying veneer, in combination, a series of substantially horizontal supporting bars on opposite sides of the machine, a plurality of return bends adapted to be supported upon said bars, a plurality of pipes connecting said return bends on opposite sides of the machine, said return bends at one side of the machine being disposed with relation to corresponding bends on the other side of the machine in such a manner that the pipes connecting them form a continuous coil, and wire mesh fastened to said pipes forming a substantially plane drying and pressing surface.
28. In apparatus for drying veneer, in combination, a movable frame comprising upright columns and substantially horizontal supporting bars attached thereto, a plurality of fixed bearings, a shaft mounted in said bearings, means attached to said shaft and connected to said upright columns, means for rotating said shaft whereby said frame is moved, and drying platens adapted to be supported by said horizontal bars, said platens being so formed and mounted that they may adapt themselves to variations in the thickness of sheets of veneer upon which they are adapted to rest while drying the same.
29. In apparatus for drying veneer, in combination, a pair of frames, each of said frames comprising upright columns and substantially horizontal supporting bars attached thereto, drying platens carried upon said supporting bars, each of said platens comprising a plurality of pipes, means fastened to said pipes forming a substantially plane drying and pressing surface, and return bends to which said pipes are connected, said return bends being adapted to rest upon said supporting bars and being formed and those of one platen being so disposed with relation to those of an adjacent platen that the plane surfaces of said platens may

- 6
- come into contact without contact between the return bends of said adjacent platens.
30. In a machine for drying veneer, in combination, a pair of frames, each frame 5 consisting of upright members and substantially horizontal members connected thereto, drying platens carried by said horizontal members, and means adapted to relatively move one of said frames to impose the 10 weight of the platens carried thereby upon the platens carried by the other frame, said platens being so constructed that they may automatically adjust themselves to any variations of the surface upon which they rest.
15. 31. In apparatus for drying veneer, in combination, a pair of frames, each of said frames comprising upright columns and substantially horizontal supporting bars attached thereto, drying platens carried upon 20 said supporting bars, each of said platens comprising a plurality of pipes, means fastened to said pipes forming a substantially plane drying and pressing surface, return bends to which said pipes are connected, and 25 means adapted to relatively move one of said frames to impose the weight of the platens carried thereby upon the platens car-

ried by the other frame, the return bends being formed and those of one platen being so disposed with relation to those of an adjacent platen that the plane surfaces of said platens may come into contact without contact between the return bends of said adjacent platens.

32. In a drying platen, in combination, a 35 plurality of pipes, means fastened to said pipes forming a substantially plane drying and pressing surface of said platen, and means attached to the ends of said pipes permitting the passage of a heating medium 40 through said pipes.

33. In a drying platen, in combination, a plurality of pipes, wire mesh fastened to said pipes forming a substantially plane drying and pressing surface of said platen, 45 and means attached to the ends of said pipes permitting the passage of a heating medium through said pipes.

In testimony whereof I affix my signature, in the presence of two witnesses.

CHAS. HARLEY.
